US00D606717S

(12) **United States Design Patent**
Xia

(10) **Patent No.:** **US D606,717 S**
(45) **Date of Patent:** **** Dec. 22, 2009**

(54) **HAND-HELD DRAIN CLEARING DEVICE**

(76) Inventor: **Hong Xia**, Room 1501, No. 27, Lane 259, Tian Deng Road, Xu Hui District, Shanghai (CN) 200030

(**) Term: **14 Years**

(21) Appl. No.: **29/311,883**

(22) Filed: **Jul. 22, 2009**

(51) **LOC (9) Cl.** **08-99**

(52) **U.S. Cl.** **D32/35**

(58) **Field of Classification Search** **D32/35, D32/40, 45, 52; D4/146, 114, 121, 127, D4/130, 132-133, 136, 138; 15/105.52, 15/107, 114, 118, 237, 142, 104.92, 21.1, 15/320-321, 323, 406; 401/146, 6, 268, 401/118, 123, 131; 294/19.1, 49; 4/255.11**

See application file for complete search history.

(57) **CLAIM**

The ornamental design for a hand-held drain clearing device, as shown.

DESCRIPTION

FIG. 1 is a space view of a hand-held drain clearing device showing my new design;

FIG. 2 is a front view thereof;

FIG. 3 is a back view thereof;

FIG. 4 is a left view thereof;

FIG. 5 is a right view thereof; and

FIG. 6 is a top view thereof; and,

FIG. 7 is a bottom view thereof.
